UNITED STATES PATENT OFFICE.

LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION OF PENNSYLVANIA.

FURNACE-DOOR FRAME.

1,118,428.

Specification of Letters Patent.

Patented Nov. 24, 1914.

Application filed January 10, 1914. Serial No. 811,388.

To all whom it may concern:

Be it known that I, LUTHER L. KNOX, a citizen of the United States, residing at Avalon, in the county of Allegheny and State of Pennsylvania, have invented a new and useful Improvement in Furnace-Door Frames, of which the following is a full, clear, and exact description, reference being had to the accompanying drawings, forming part of this specification, in which—

Figure 1 is a front elevation partly broken away of one form of door frame embodying my invention; Figs. 2, 3, and 4 are sections taken, respectively, on the lines II—II, III—III and IV—IV of Fig. 1; Fig. 5 is a front elevation of a modified form of door frame; Figs. 6 and 7 are sections taken, respectively, on the lines VI—VI and VII—VII of Fig. 5; Fig. 8 is a front elevation partly broken away, showing another form of door frame applied to a furnace; Figs. 9 and 10 are sections taken, respectively, on the lines IX—IX and X—X of Fig. 8; Fig. 11 is a front elevation partly broken away showing still another form of door frame embodying the invention; Figs. 12, 13 and 14 are sections taken, respectively, on the lines XII—XII, XIII—XIII and XIV—XIV of Fig. 11; Fig. 15 is a plan view of the blank which may be used in making the upper or lintel portion of the door frame shown in Fig. 1; Fig. 16 is a view partly in front elevation and partly in vertical section showing die mechanism and illustrating the first step of forming the arch in said upper or lintel portion; and Fig. 17 is a vertical section of the die mechanism and showing the second step of forming such arch.

My invention has relation to door frames for furnaces, and more particularly to hollow water-cooled door frames formed from sheet metal.

The object of my invention is to provide a door frame of this character which can be readily constructed from sheet metal; in which the seams are located at such points as to be away from the door opening through the frame, and therefore, not liable to become injured by contact with the charging mechanism or other tools introduced into the furnace, and also to improve the construction in other respects, as hereinafter more fully pointed out.

Referring first to the form of my invention shown in Figs. 1 to 4, inclusive, the numeral 2 designates the upper or lintel portion of the frame, and 3 the depending legs, one at each side of the door opening 4. The portion 2 is united to the upper extensions 3^a of the legs 3, by welds formed along the lines a—a. This portion 2 is formed by taking a sheet of metal forming the arch 5, at the center portion of the sheet, then bending the sheet upon itself into U-form, as clearly shown in Fig. 2, and then closing the upper end of the hollow body so formed by means of a separate top plate 6, welded to the upper edges of the sheet. The lateral edges of the U-shaped body are welded to the inner free edges of the leg extensions 3^a. It will be noted that the arch 5 is formed integrally in the metal sheet constituting the portion 2. In Figs. 16 and 17, I have illustrated the manner in which this arch is formed. The initial form of the sheet or blank is substantially that shown at A in Fig. 15. The lateral edges of the sheet are preferably somewhat tapered, so as to narrow the sheets toward both ends to take care of distortion of the metal during the forming operations. The sheet is also laterally recessed at A', at its central portion, in order to compensate for the distortion of the metal in forming the arch and to properly shape the ends of the arch to fit the shoulders 7 of the leg portions of the frame. This sheet is placed in a machine having the vertically movable dies B B', and the lower die is then moved upwardly, as shown in Fig. 16, thereby pressing the central portion of the sheet contained between the dotted lines A²—A² of Fig. 15 upwardly into arch form. Pressure is held on the lower die B', and the upper die B is then moved downwardly with sufficient pressure to overcome the pressure on the lower die, carrying the sheet downwardly between the former portions C (Fig. 17), thereby bending the sheet into the U-shape, while still retaining the arch in the bottom portion. These operations may distort the sheet somewhat, so that it will require some trimming before welding. It may also be necessary in some instances to further work the blank to remove some of the distortions resulting from the die operations. Each of the leg portions 3, 3^a is preferably formed from a single piece of

metal bent into hollow rectangular form with the forwardly offset portion 8, the inner wall 9 of which acts as a guide for the furnace door. The free edges of each leg-forming blank are welded together at the outer forward corner 10, this weld extending continuously from the top to the bottom of the door frame. The upper portion of the inner wall of the leg thus formed, and 10 which is to be united to the lintel portion 2, is then cut away, as shown in Fig. 3, so as to give free edges to be welded to the edges of said portion 2. The sheet metal body may be stiffened or braced by means 15 of connectors 11, which may be in the form of stay bolts. The frame may be provided with any suitable connections for circulating water through its interior. In the form shown in these figures, I have shown one of 20 the legs as having a vertical pipe 12, extending downwardly therein from the upper end and terminating at a point a short distance from its lower end. This pipe has a branch 13, connected thereto, and which 25 extends transversely over the arch 5 and thence downwardly within the lower portion of the other leg. This branch pipe may be provided with suitable discharge 30 perforations 14, above the arch 5, so as to discharge cooling water directly against the wall of the arch. The numeral 15 designates an offtake connection, located at one 35 of the upper corners of the frame, and 16 is a suitable blow-out or clean out plug located at the lower portions of the legs. By 40 these connections, a continuous circulation of water may be kept up throughout the entire frame. It will be noted that, except at the shoulders 7, there are no welds in 45 the structure adjacent the upper opening. This is an important feature of the invention, since when such welds are located at the upper opening, they may be injured or opened up by contact with the charging apparatus or other tools introduced through the door into the furnace.

The structure shown in Fig. 5 differs from that shown on sheet 1, in that the door opening 4^a is somewhat higher, the arch at the 50 top of the opening is omitted, and the lintel portion 2^a is formed at its lower edge with a rearward lateral projection 2^b, which forms a metallic wall over the door opening in the furnace wall, in the manner described 55 and claimed in my Patent No. 1,070,487, of August 19, 1913.

The structure shown in Figs. 8, 9 and 10 differs from the structure shown on sheet 1 in two respects, namely, instead of forming 60 the lintel portion in a single U-shaped sheet, closed at the top by a flat strip or plate, this portion is constructed of two U-shaped blanks 17 and 18, the upper blank being inverted and its free edges being welded to 65 the upper free edges of the lower blank

along the horizontal transverse weld lines 6-6. The lower blank 18 has the arch 19 formed therein in substantially the same manner as in the form first described. The second respect in which the structure shown 70 in these figures differs from that first described is in the provision of a hollow transverse connecting or tie member 20, which unites the lower ends of the depending legs. This member is preferably formed of a single sheet or strip of metal, bent to form a hollow rectangular shape, with its edges welded together at c. The ends of this shape are open; the inner lower portions of the legs are cut away at 21, and the free ends 80 edges of the member 20 are welded to the edges of these cut-away portions. In order to provide for an efficient circulation through this bottom tie connection, the water supply pipe 12^a is preferably provided with a bent portion 12^b at its lower end, which extends a short distance into one end of this connection. The branch supply pipe 13^a also preferably terminates 85 above the arch 19, and does not extend downwardly with the leg at the opposite side. This bottom connection or tie is a feature of considerable advantage in practice, since it effectually holds the leg portions of the frame against spreading or twisting in use. 95

In the construction shown in Figs. 11, 12, 13 and 14, the structure is formed in three separate pieces, namely, the upper or lintel portion 22, and the two legs 23, the upper portion 22 resting on the upper ends of the 100 legs. The upper or lintel portion 22 is constructed in substantially the same manner as that first described and shown on sheet 1, except that the arch 24 terminates at the inner vertical edges of the legs, and a flat 105 portion 25 is provided at each side of the arch to rest upon the upper end of the leg. Each of the legs is preferably formed from a single piece of metal in the same manner as before described. The structure is shown 110 as having two vertical water supply pipes 26, one extending downwardly to a point near the lower end of each leg. The legs are of greater depth than the upper or lintel portion, as clearly shown in Fig. 12, and the 115 upper portions of the pipes 26 extend up outside of and in front of said lintel portion, with their inner edges substantially in vertical alinement with the vertical door-guiding surfaces 26^a of the legs. In this 120 manner, the upper portions of these pipes are utilized as door guides. The top plate 27 of the lintel may be provided with suitable clips 28, to receive and secure the upper end portions of these pipes. The water discharged at the lower ends of the pipes 26 rises in the legs as it becomes heated and passes out through the pipe connections 29, which lead into the lower portion of the 125 lintel, and are provided with horizontally 130

extending discharge branches 30 therein. The lintel is provided with the central off-take 31, at its upper end. The water is thus made to circulate first through the legs and 5 then through the upper portion or lintel.

It will be noted that in all the forms of the invention, the structure is made with a minimum number of welds, and that these are located away from the door openings in 10 the manner and for the purpose before described.

It will be obvious that my invention is susceptible of various other modifications and that many changes may be made in the 15 details thereof, without departing from the spirit and scope of the appended claims.

I claim:

1. A furnace door frame having an upper or lintel portion, comprising a sheet metal member bent into U-shape in vertical section, and a closure united to the free edges of said member; substantially as described. 20
2. A furnace door frame having an upper or lintel portion, comprising a sheet metal member bent into U-shape in vertical section, said member having a transverse arch formed integrally in the closed U-bend of its lower portion; substantially as described. 25
3. A hollow, sheet metal, water-cooled door frame, comprising a lintel portion and depending leg portions, the lintel portion being united to the leg portions by vertical welds and the leg portions formed from sheet metal blanks having their edges welded at points remote from the edges of the door opening between the legs, substantially as described. 30
4. A hollow, sheet metal, water-cooled door frame, comprising a lintel portion and depending leg portions, the lintel portion being united to the leg portions by vertical welds and the leg portions formed from sheet metal blanks having their edges united 45 by welds located at the outer forward corner portions thereof, substantially as described.
5. A hollow, water-cooled sheet metal door frame, comprising an upper lintel portion, depending leg portions, and a hollow tie or connecting member uniting the lower ends of the leg portions, said portions all having communicating water spaces and connections for effecting a water circulation therethrough, said lintel portion, depending leg portions, and connecting member being formed from a sheet metal blank and having their adjacent edges integrally connected to form a unitary sheet metal structure, substantially as described. 50
6. A hollow, sheet metal, water-cooled door frame, comprising an upper or lintel portion and depending leg portions, and a hollow tie portion connecting the lower ends 60

of the legs, said legs having openings communicating with the interior of the tie portion, said upper or lintel portion, depending leg portions and the hollow tie portion being each formed by a shaped sheet metal blank, and the adjacent edges of said portions being integrally united to form a unitary sheet metal structure, substantially as described. 65

7. A hollow, water-cooled sheet metal door frame, comprising an upper or lintel portion formed from two sheets or blanks, each bent into U-shape and united at their free edges, the joint between the two blanks being above the bottom of the lower blank and removed from the door opening of the 80 frame, substantially as described. 75

8. A hollow, water-cooled, sheet metal door frame, comprising an upper or lintel portion formed from two sheets or blanks, each bent into U-shape and united at their free edges, the lower sheet or blank having an arched bottom formed integrally in the U-bend at the bottom thereof, substantially as described. 85

9. A hollow, sheet metal door frame, comprising an upper or lintel portion and depending leg portions, the lintel portion having a U-shaped lower member, the leg portions being cut away at their inner sides opposite said U-shaped member, and the free edges of the U-member being united to the free edges of said cut-away portions, substantially as described. 90

10. A hollow, sheet metal door frame, comprising an upper or lintel portion and depending leg portions, the lintel portion having a U-shaped lower member, the leg portions being cut away at their inner sides opposite said U-shaped member, and the free edges of the U-member being united to the free edges of said cut-away portions, substantially as described. 100

11. A furnace door frame, comprising an upper or lintel portion and depending leg members, said leg members being of greater horizontal depth than the lintel portion, and water supply pipes extending downwardly into said leg portions, the upper portions of said pipes lying in front of the lintel and forming door guides, substantially as described. 115

12. A furnace door frame, comprising an upper or lintel portion and depending leg members, said leg members being of greater horizontal depth than the lintel portion, and water supply pipes extending downwardly into said leg members, the upper portions of said pipes lying in front of the lintel and forming door guides, and said leg members having door-guiding surfaces in vertical alignment with the guiding surfaces of said pipes, substantially as described. 120

4

13. In a furnace door frame, a leg member whose body is formed from a single piece of sheet metal bent upon itself and having its edges welded to each other at an outer corner thereof, and end plates secured to and closing the ends of said body, substantially as described.

In testimony whereof, I have hereunto set my hand.

LUTHER L. KNOX.
